UNITED STATES PATENT OFFICE.

RICHARD E. COLE, OF COLUMBUS, OHIO.

CONTAINER.

1,411,365.

Specification of Letters Patent. Patented Apr. 4, 1922.

Application filed October 15, 1920, Serial No. 417,172. Renewed August 19, 1921. Serial No. 493,685.

To all whom it may concern:

Be it known that I, RICHARD E. COLE, a citizen of the United States of America, residing at Columbus, in the county of Franklin and State of Ohio, have invented certain new and useful Improvements in Containers, of which the following is a specification.

My present invention relates generally to containers of that nature designed to protect the contents thereof from external influence, and resides more particularly in a container for preserving photographic films, plates and the like as well as blue print papers and other materials detrimentally affected by the ordinary atmosphere and especially damp air.

The primary object of my invention is the provision of a container of this nature which will be capable of more or less rough handling in use as well as transportation and which provides for ready introduction or removal of the material to be stored or shipped.

A further object is the provision of a container having means whereby to defeat ill effects of carelessness in failing to replace the lid, and a still further object is the provision of a comparatively simple inexpensive and durable container in connection with which the air drying chemicals or compounds may be readily renewed from time to time, and conveniently held therein.

In the accompanying drawing, which illustrates my invention and forms a part of the specification,

Figure 1 is a front elevation.

Figure 2 is a central vertical section.

Figure 3 is an enlarged vertical section taken on line 3—3 of Figure 1, and

Figures 4 and 5 are enlarged horizontal sections taken respectively on lines 4—4 and 5—5 of Figure 2.

Referring now to these figures, the body 10 of my improved container is preferably of vertical cylindrical form with a doubled internal annular rib 11 adjacent to its edge on which rib a base plate 12 is seated. This rib 11 thus not only reinforces the lower edge of the container body, but also receives thereon and supports the base plate, whose peripheral edge snugly interfits the cylindrical body 10.

The lower portion of the body has an outer reinforcing wall 13 surrounding the same in close contact therewith and pro-

vided at points above the base plate 12, with vertically spaced outer annular ribs 15 which serve to further reinforce and strengthen the lower portion of the body 10.

A false bottom 16 is preferably formed of heavy mesh screening material secured at its periphery to a ring 17 the latter of which has at circumferential spaced points depending legs 18 whose lower angular ends 19 rest on the base plate 12. In reality however this false bottom forms the base of the chamber within body 10 which chamber above the reticulate base receives the films, plates, blue print papers, etc. to be preserved against deterioration, and its nature is such as to place this material receiving chamber in open communication with the compartment of the body existing between the false bottom 16 and the base plate 12. This last mentioned compartment receives chemical holding bags 20 preferably in the shape shown in Figures 2 and 5 so that they may be separately introduced through the upper end when the reticulate base has been removed.

Each of the bags 20 in practice contains a dry powdered or granular chemical or other suitable material for absorbing moisture out of the air within the container, material in the form stated being preferred although it may be of liquid form except in case of shipment.

The upper edge of the body 10 is preferably flanged for added strength and also has vertically spaced inner annular ribs 21 below said edge, the upper rib 21 forming a supporting ring for the inner closure plate 22 of the material receiving chamber. This plate is of less diameter than the body 10, and has an upper handle 23, and a depending apertured lug 24, the latter receiving the upper end of a controlling spring 25, preferably a coil spring. The lower end of this spring is connected to an eye-bolt 14 connected to, and projecting upwardly from the center of the reticulate base 16.

The final closure or cover 26 has an inwardly tapering lower flange 27 adapted to telescope within the upper flanged edge of the body 10 and provided with an outer handle 28. This cover closes in practically air-tight relation on the body when properly seated, and it is to avoid the disadvantage of improper seating or failure to put the cover on, that the spring controlled closure plate 22 is provided.

It is obvious that upon proper seating of the cover on the body some pressure or excess of air is entrapped and to relieve all such excess with the exception of just sufficient pressure to assist in holding the closure plate 22 in place, the cover 26 has small air valves 29 similar for instance to tire valves, opening outwardly and closing inwardly under small spring pressure.

10 After material, for instance rolls of blue print paper, is placed within the receiving chamber, resting on the false bottom 16, by first removing the cover 26 and lifting the closure plate 22, the latter is released and finds its way to properly seated position with the assistance of its spring 25. The cover 26 is then replaced in the position shown particularly in Figure 2, and any air finding its way into the chamber is at once dried out and sterilized by the chemicals in the lower bags 20.

15 In case of storage, particularly for any great length of time, authorized persons will inspect and renew the chemicals if this becomes necessary, and it is obvious that by using proper chemicals the air throughout the space within the body 10 will be maintained in a dry state so as to prevent deterioration of the materials placed therein whose 20 preservation is desired.

25 The false bottom or reticulate base 16 is normally held down with its legs resting on the base plate 12, by means of an annular series of lugs 30, connected in place by bolts 32 passing through the cylinder wall and externally apertured for the reception of seals 31. Thus unwarranted removal of the reticulate bottom 16 for removal or 30 change of the chemicals can be defeated by ready detection.

35 I claim:—

1. A container of the character described having a vertical cylindrical body provided with a closed base and a removable top closure, a reticulate member within the body 40 dividing the same into an upper relatively

large storage compartment and a lower relatively small chemical holding compartment, and chemical holding means within the lower compartment and sealed means for 50 clamping said reticulate member in place.

2. A container of the character described having a closed base, a reticulate bottom spaced above the base and dividing the container into intercommunicating chambers, 55 chemical holding means in the lower chamber, a top closure through which access may be had to the upper chamber and means working through the side of the container for clamping said reticulate bottom to the 60 container base.

3. A container having a top closure and closed base, a reticulate bottom therein spaced above the base, means acting to clamp the said bottom to the base, and a cover plate 65 in the upper portion of the container resiliently connected to the said reticulate bottom and shiftable vertically through the upper end of the container when said top closure is removed.

4. A container having a top closure and closed base, a reticulate bottom therein spaced above the base, lugs within the container normally engaging and clamping the said reticulate bottom to the base, and 70 clamping bolts for the lugs extending through the wall of the container and having seal receiving means.

5. A container having a removable top closure including a cover and a closure plate 80 seated within its upper portion below the cover and shiftable above the container when the cover is removed, a closed base, a reticulate bottom spaced above the base, internal supports for said reticulate bottom clamping 85 the same to said base, and a spring extending vertically in the container from said reticulate bottom and connected to and controlling the said closure plate.

90 In testimony whereof I have affixed my signature.

RICHARD E. COLE.
